[57] CLAIM

The ornamental design for an image scanner for electronic computers, as shown and described.

DESCRIPTION

FIG. 1 is a top, right side and front perspective view of an image scanner for electronic computers showing my new design,

FIG. 2 is a front elevational view thereof,

FIG. 3 is a rear elevational view thereof,

FIG. 4 is a top plan view thereof,

FIG. 5 is a bottom plan view thereof,

FIG. 6 is a right side elevational view thereof,

FIG. 7 is a left side elevational view thereof, and

FIG. 8 is a top, right side and front perspective view thereof on a reduced scale, the paper feeding tray being shown in broken lines for illustrative purposes only.

FIG. 1

FIG. 2

FIG. 3

FIG.4

FIG.5
